PHILIP WATSON PRATT, OF BOSTON, MASSACHUSETTS, ASSIGNOR TO CHARLES F. BROWN, TRUSTEE, OF READING, MASSACHUSETTS.

HEEL-CUSHION.

No. 863,873.

Specification of Letters Patent.

Patented Aug. 20, 1907.

Application filed August 5, 1905. Serial No. 272,852.

To all whom it may concern:

Be it known that I, PHILIP WATSON PRATT, of Boston, in the county of Suffolk and State of Massachusetts, have invented certain new and useful Improvements in Heel-Cushions, of which the following is a specification.

This invention relates to cushions adapted to be inserted in the interior of a shoe, the embodiment here shown being particularly designed for insertion and attachment to the heel portion, although it may be intended to constitute an entire internal sole.

The invention has for its object to provide an article of resilient material, such as rubber, which will have a high degree of resilience under the vertical pressure exerted on it by the weight of the wearer of the shoe, and will be prevented from spreading laterally or crosswise of the shoe so that its resilience will be maintained and will not be diminished materially by compression due to the weight of the wearer.

20. Of the accompanying drawings.—Figures 1 and 2 represent perspective views of a resilient pad forming a part of my improved cushion structure, the pad being shown as it appears before the fastening devices herein-after referred to are applied. Fig. 3 represents a vertical longitudinal section showing a complete embodiment of my invention, including the said fastening devices. Fig. 4 represents a perspective view of another form of pad shown as it appears before the fastening devices are applied. Fig. 5 represents a sectional view 30 showing the form of pad represented in Fig. 4, and including the fastening devices. Fig. 6 represents a sectional view of another form of pad shown without the fastening devices. Fig. 7 represents a perspective view of the assembled cushion, including the fastening devices.

The same reference characters indicate the same parts in all the figures.

The cushion consists of a resilient pad *a*, preferably of rubber, having the portion *b* adjacent the shank part 40 of the shoe when it is in place, formed with a thin edge, a leather lift or tread-piece *c*, and a fabric bottom-piece *d*. The tread-piece is skived to a thin edge at that part which comes adjacent to the shank of the shoe and, it may be connected to the pad and the bottom-piece 45 at the tapered part by a line of stitching extending transversely across the cushion, or by cement. The tread piece is positively secured to the pad by rows of fastenings *r* which are preferably eyelets, the rows extending lengthwise of the cushion or from the breast 50 end toward the rear or heel end. The piece *d* is secured by pasting or cementing to the inner sole or sock-lining, thereby preventing the pad and tread-piece from working forward.

The pad is formed on the lower surface with transverse 55 ribs *g* having an arched form and separated by grooves *i*.

Intermediate the grooves *i* and centrally arranged with respect to the arched ribs *g* are transverse passages which, in the form of the invention shown in Figs. 1, 2 and 3, are made as open grooves *i*, and in that of Figs. 4 and 5 are inclosed passages *i* wholly surrounded, except at their ends, by the rubber of which the pad is composed. The legs *h* of the form shown in Fig. 3, are therefore common to the arches of both series, and this arrangement gives this pad the appearance of being formed of corrugations on both surfaces, while the other form is corrugated on its lower side only. The ribs on the upper side of the pad of Figs. 1, 2 and 3, are formed with flattened crowns *e* having square corners, and they are arranged in the same plane so that they constitute practically a continuous surface broken by the grooves *i* which come 70 opposite the crowns of the arches *g*. This gives an extended bearing for the tread-piece *c* and causes a strong frictional engagement so that when pressure is applied upon the tread-surface, the tendency of the pad to give way and move bodily out from under the heel of the wearer, is resisted, and the pad held in place and practically the whole pressure caused to come directly upon the legs of the arches, causing them to be compressed, while remaining in place with scarcely any lateral separation.

The arches *g* on the under side of the pad are rounded and they are held from separating when pressure is applied by means of a flange *l* formed upon the pad extending about its periphery and connected to the ends of the arched ribs, tying them together. Ventilating 85 holes *o* extending through the crowns of the arched ribs are formed in the pad.

Preferably the thickness of the material forming the crowns of the arches is less than the depth of the grooves, so that the grooves on each side of the pad extend beyond the bottoms of those on the other side, their bottom portions thus overlapping. This structure provides that all the weight borne by the pad is supported by the legs of the arches and permits a great amount of yielding before the crown portions of the upper arches 95 are pressed against the sole of the shoe. Thus the maximum of resiliency is obtained together with a saving in the amount of rubber necessary to make the pad. In order still further to prevent the pad from spreading out and creeping longitudinally when pressure is applied to it, there may be provided, if desired, in addition to the flange *l* and the structure producing frictional engagement between the upper side of the pad and the tread-piece, tie-pieces, ribs or bridges extending across the grooves *i* between and connected to the transverse arched ribs on the upper side of the pad. These tie members will, as stated, tend to prevent elongation of the pad under pressure and so increase the elastic resistance of the latter to compression. This idea is carried out to a greater extent and in a way 105 110

which interferes less with the resiliency of the pad, in the form of the invention illustrated in Figs. 4 and 5, where the transverse passages i' , corresponding to the grooves i of the form first described, are covered over by integral portions j of the pad, which are slightly arched upward. Thus the upper side of this form of pad has a continuous surface composed of the level portions e' above the grooves f in the lower side, corresponding to the flat crowns e of the upper ribs in the previously described form, and alternating low, flexible ridges. The bridging layers j , since they can easily collapse into the passages i' when downward pressure is applied by the weight of the wearer, do not in any way limit or reduce the degree of elasticity of the pad, while they do resist its tendency to elongate under pressure by exerting a direct elastic pull in opposition to any force tending to separate the portions e' above the grooves f .

It will be seen that the pads above described, particularly the latter form, furnish for a heel an internal cushion which is soft and capable of yielding by a considerable amount without losing its elasticity and becoming hard, securing these results with the necessity of using only a minimum amount of rubber. The transverse grooves and passages, together with the holes leading to the upper and lower surfaces of the pad also provide means by which a circulation of air is secured and thus the interior of the shoe is ventilated.

In Fig. 6 I show in section, a heel shaped rubber pad having in its upper sides transverse grooves f^2 , and in its lower side transverse grooves f^3 alternating with the grooves f^2 , said grooves extending entirely across the pad. The grooves of each series are separated by ribs having flattened crowns constituting the upper and lower faces of the pad. To said upper and lower faces are secured inextensible or non-elastic pieces or layers V formed to entirely cover said faces, and composed of textile fabric, said pieces being vulcanized or otherwise secured to the pad and serving, like the flange l , to tie the ridges together, and thus prevent elongation of the pad under vertical pressure. The pieces V are therefore the equivalent of the flange l , the latter providing elastic ties between the ribs, while the parts V constitute inelastic ties between the ribs.

45 One of the pieces V may be omitted if desired.

The above-mentioned fastenings r are preferably eyelets which pierce the tread and the pad between the ribs, the ends of the eyelets being flanged over, both at the upper surface of the tread-piece and at the inner limits of the grooves f . These eyelets are preferably made in two parts consisting of an outer shell r' and a lining r^2 of dissimilar metals, one of which may be electro-positive to the other, and when so made are preferably copper and zinc, the outer shell being of zinc, while the lining piece is copper. These metals are in contact and are exposed at their ends on the ex-

posed surface of the lift c so that contact may be made with them by the foot of the wearer. Thus each eyelet constitutes a galvanic couple which sets up an electric current in the foot of the wearer when contact is made. The central orifices s of the eyelets also provide passages through which the air displaced by compression of the pad is forced, and thereby the shoe is ventilated. Additional perforations t are formed in the tread-piece to permit free passage of the air and thus provide a more thorough and complete ventilation. It will thus be seen that the cushion not only serves the function of diminishing shock while walking but also ventilates and produces a galvanic action upon the foot of the wearer.

The chief function of the fastenings r is to assist in preventing longitudinal and lateral spreading out of the cushion when pressure is applied to it by the weight of the wearer, and accordingly, they are arranged in longitudinal lines in the cushion. They bind the relatively inextensible leather tread piece to the rubber cushion at a plurality of points extending from the front toward the rear thereof, and so assist in keeping it compact. Thus the weight of the wearer can only compress the ribs, there being no opportunity for them to flatten by bending forward, and the full resilience of the rubber is capable of utilization. By this means as much elastic resistance to the weight of the wearer is furnished as would be if the cushion were of solid rubber, while a great saving of material is effected.

In using the cushion, the fabric layer d may or may not be omitted according to preference. If this layer is used and stuck to the insole of the shoe, it will effectively prevent the part of the cushion which is under the shank of the foot from rising and also prevent the cushion from working forward, but such movement is also prevented by the flange l or the fabric layers V , while the eyelets prevent separation and displacement of the leather tread-piece from the cushion.

It is to be understood that the cushion shown in Fig. 6 is provided with fasteners r , such as those shown in Figs. 5 and 7. Said fasteners are not shown in Fig. 6 because the latter is a sectional view on the median line of the cushion, the fasteners r being at opposite sides of said median line.

100 I claim:

A cushion for shoes comprising a yielding pad formed with ribs and intermediate spaces, a tread-piece, and a plurality of fastenings arranged in rows or series extending lengthwise of the pad and connecting the pad and tread piece, whereby the pad is permitted to yield vertically under the weight of the user and is prevented from spreading longitudinally and laterally.

In testimony whereof I have affixed my signature, in presence of two witnesses.

PHILIP WATSON PRATT.
